UNITED STATES PATENT OFFICE.

WILLIAM E. BRADT, OF SCHENECTADY, NEW YORK, ASSIGNOR, BY MESNE ASSIGNMENTS, TO THE J. V. PILCHER MFG. CO., INCORPORATED, OF LOUISVILLE, KENTUCKY.

CUFF-HOLDER.

SPECIFICATION forming part of Letters Patent No. 683,548, dated October 1, 1901.

Application filed May 21, 1900. Serial No. 17,322. (No model.)

To all whom it may concern:

Be it known that I, WILLIAM E. BRADT, a citizen of the United States, residing at Schenectady, county of Schenectady, and State of New York, have invented certain new and useful Improvements in Cuff-Holders, of which the following is a specification.

The invention relates to such improvements; and it consists of the novel construction and combination of parts hereinafter described and subsequently claimed.

Reference may be had to the accompanying drawings, and the reference characters marked thereon, which form a part of this specification.

Similar characters refer to similar parts in the several figures.

Figure 1 of the drawings is a view in vertical longitudinal section of a portion of a coat-sleeve and a detachable cuff, showing my improved cuff-holder attached to the cuff and in the operation of being attached to a coat-sleeve. Fig. 2 is a top plan view of the cuff-holder detached. Fig. 3 is a cross-section of the same, taken on the broken line 33 in Fig. 2. Fig. 4 is a plan view of a bifurcate pin detached.

The object of my invention is to provide a simple and efficient mechanism for detachably connecting an apparel-cuff with the lining of a coat-sleeve.

My improved holder comprises a metallic plate 1, provided at or near one end with one or more longitudinal slideways 2 and at or near the other end with a like number of pin-point sheaths 3 in line with said slideways. I prefer to employ two slideways and a like number of sheaths, as shown. The plate 1 presents a continuous body and upper surface between said slideways and sheaths. The bifurcate pin 4 is supported by said plate with its bifurcate members located in said slideways and adapted to reciprocate therethrough to and from the respective sheaths. The ends of the pin are sharply pointed and adapted to traverse the space between said slideways and sheaths in close proximity to the upper surface of the plate 1. The plate is also provided with a T-shaped spring 5, having its T-head adapted to bear upon the upper side of the pin and enter notches 6,

formed therein, to yieldingly lock the pin at the limits of its intended movement. The plate, slideways, sheaths, and spring are preferably formed from a single piece of sheet metal cut, slotted, and bent at one end to form a T-spring, and adjacent thereto the respective slideways, and near the other end to form the sheaths, the slideways and sheaths being both formed in the manner illustrated in Fig. 3.

The mechanism above described comprises a means for detachably securing the holder to the lining of the coat-sleeve. The holder may be detachably secured to an apparel-cuff in any known manner.

I have shown one end of the plate reverted at 7 to form a support for a pivoted clamping-tongue 8, provided with the lever-handle 9 and adapted to coöperate with the under surface of the plate 1 to form a clamp for detachably securing the holder to a cuff inserted therein.

The operation of the device is as follows: The holder is first applied to the cuff 18 and secured thereto in any known manner, after which the cuff, with the holder attached, is inserted within the coat-sleeve to the desired distance. The pin being withdrawn from the sheath, the operator presses against the head 17 of the pin with his thumb 13 to insert the same, while at the same time he forces the fabric of the coat-sleeve with one of his fingers 14 down upon the body of the plate 1, between the slideways and the sheaths, thereby causing the pin to pass through and connect with the inner portion of the coat-sleeve before the points of the pins enter the sheaths. By providing the plate 1 with a continuous supporting-surface between said slideways and sheaths and causing the points of the pin to traverse a path in close proximity to such surface I am able to limit the amount of fabric which can thus be forced into the path of the pin, and thus cause the pin to penetrate 95 and connect with only the lining 10 of the coat-sleeve, the plate preventing the body fabric 12 of the sleeve from entering the path of the pin. I am thus able to detachably and securely connect the cuff with the coat-sleeve 100 without any external evidence of such connection.

My improved holder is easily and quickly applied to support the cuff in any desired position within the sleeve.

The bifurcate members of the pin are preferably provided with straight-pointed prongs 16 of comparatively small diameter and of a length equal to the distance between the slideway and sheath and comprising the penetrating portion of the pin. By employing such a construction not only is the penetration of the pin facilitated, but I am able to support the larger members 4 of the pin directly upon the plate 1, as shown in Fig. 3, the difference in diameter of said prong and member 4 causing the point to traverse a path a short distance above and in close proximity to the surface of said plate.

What I claim as new, and desire to secure by Letters Patent, is—

- 20 1. A cuff-holder comprising in combination a supporting-plate provided with a pin-slideway and sheath; means for detachably securing the same to a cuff; and a pin having a cylindrical sliding member of comparatively large diameter adapted to reciprocate in said slideway upon the surface of said plate, and a cylindrical, pointed, penetrating prong of less diameter than said sliding member and formed integral therewith, substantially as described.
- 25 2. A cuff-holder comprising in combination a pair of parallel pin-slideways; a pair of sheaths for the pin-points; and a continuous, closed, supporting plate or body extending

from said slideways to said sheaths; means 35 for detachably securing said plate to a cuff; and a bifurcate pin comprising a yoke, a pair of parallel, cylindrical members of relatively large diameter reciprocatory through said slideways upon the surface of said plate, and 40 a pair of cylindrical, pointed members of relatively small diameter reciprocatory to and from said sheaths in close proximity to the surface of said plate and adapted to connect with the lining only of a coat-sleeve, sub- 45 stantially as described.

3. A cuff-holder comprising in combination a supporting-plate, provided with a pin-slideway and sheath, and having a continuous surface therebetween in the same plane with the bottom of said slideway; means for detachably securing the plate to a cuff; and a pin having a cylindrical sliding member of comparatively large diameter adapted to rest and slide upon the bottom of said slideway 55 and surface of said plate, and a cylindrical pointed member of comparatively small diameter adapted to reciprocate to and from said sheath at a distance above the surface of said plate equal to one-half the difference in diameter of said member, substantially as described.

In testimony whereof I have hereunto set my hand this 14th day of May, 1900.

WILLIAM E. BRADT.
